PANAYIOTIS D. PANOULIAS, OF JERSEY CITY, NEW JERSEY.

CONFECTION-COATING MACHINE.

1,304,362.

Specification of Letters Patent. Patented May 20, 1919.

Application filed August 20, 1918. Serial No. 250,634.

To all whom it may concern:

Be it known that I, PANAYIOTIS D. PANOULIAS, a subject of the King of Greece, and a resident of Jersey City, in the county of Hudson and State of New Jersey, have invented a new and useful Confection-Coating Machine, of which the following is a specification.

The invention relates to confectionery-coating machines, and more particularly to machines for coating candy centers with fluid chocolate by the flooding method. In apparatus of this type the centers are carried through the machine by an endless open wire conveyer or belt, or by two or more belts in series. At one stage in the progress the centers encounter a flood of the coating material; further along the coated confections may be acted upon by 20 decorating devices. It is also customary to vibrate the belt or belts in order to make the coatings smooth and glossy and to remove excess material. Not infrequently the confections become laterally displaced by 25 the flood or as the result of the tapping, so that the pieces touch each other and imperfect coatings are produced, in addition to which the alinement which may be desirable for subsequent operations is lost. One 30 of the objects of the invention is to provide in a simple and effective way for compartments or stalls in the working portion of the belt, and particularly at and adjacent the flooding region, whereby such displacement 35 is prevented. This is accomplished in part by the employment of a coating belt consisting of longitudinal strands such as shown in my application Serial No. 642,090, filed August 3, 1911, together with elevating 40 guides or pulleys associated with certain of the strands to raise these above the level of the remainder, so that the longitudinal rows of confections are kept separate as they pass through the flood, and for as great a distance 45 at either side thereof as may be desired. Means are provided for changing the spacing between the elevating guides, so as to vary the widths of the confection compartments to accommodate confections of different sizes. The invention also provides in an advantageous manner for the individual tensioning of all the strands in their inactive or return stretches, which enables any of the strands to be raised in their working courses 50 without affecting the other strands.

In the accompanying drawings illustrat-

ing so much of a coating machine as is necessary for an understanding of the improvements:

Figure 1 is a vertical longitudinal section;

Fig. 2 is an enlarged view of a portion of Fig. 1;

Fig. 3 is a fragmentary transverse vertical section corresponding to Fig. 2; and

Fig. 4 is a fragmentary view looking in the direction of the arrow at the right of Fig. 1.

The coating belt shown in these views is composed of a plurality of endless longitudinal strands 1, which pass around a grooved cylinder or a series of grooved pulleys 2 on a shaft 3 at the receiving end, and about another series of grooved pulleys 4 on a shaft 5 at the exit or delivery end. A hopper 6 for delivering a flow of chocolate through the belt and over the centers α as they reach this point is indicated schematically. As is well known in the art the flood passes downward into a heated tank beneath the belt, from which it is continuously elevated to the hopper. These features, being familiar, are not illustrated. A frame 7 pivoted at 8 and vibrated up and down by ratchets 9, and carrying a bottoming plate 10 beneath the flow and under the upper course of the belt and transverse tapping bars 11, is as disclosed in my prior application aforesaid.

The numeral 12 designates a fixed bar which extends across the machine between the upper and lower courses of the belt, somewhat in advance, that is to say at the approaching side, of the flooding region, and which is suitably supported by the framework of the machine, here sufficiently represented by the side plate 13. This bar is provided with bolt holes adapted to receive bolts 14 for the attachment of a carrier 15, which may be in the form of an angle iron. The said carrier bears a series of upwardly projecting boxes 16 containing grooved pulleys 17, which are disposed at such height as to raise the upper courses of the strands with which they coöperate a sufficient distance above the general level to prevent the lateral displacement of the centers. The pulleys 17 are placed upon the carrier at intervals such as to raise only those strands of the belt which will form the sides of stalls or channels of a width corresponding approximately to the width of the confections.

The width of the stalls can be readily changed by removing the carrier 15 and replacing it with another on which the elevating pulleys are differently spaced, so as 5 to engage other of the strands. As indicated at 16^a, 17^a, part or all of the partitions can be made by raising two adjacent strands, thus securing greater separation, pulleys side by side or double pulleys being used for the 10 purpose.

By these means the confections are kept separate and in line, the proportion of damaged goods can be materially reduced, and the belt can carry more pieces and be run 15 faster without danger of mutual contact.

The fixed bar 12 is also provided, in its lower part, with a series of closely adjacent apertures 18, which receive the upper ends of depending springs 19. Supported on the 20 lower ends of these springs and urged upward thereby are blocks 20 holding grooved pulleys 21 which bear against the under sides of the strands in their lower courses and thereby keep the belt strands in proper 25 tension. The blocks 20 have entrances 22 which permit ready removal and insertion of the individual strands. Whereas there are relatively few of the elevating pulleys on the upper side of the bar, corresponding 30 to occasional strands, each strand of the belt has an individual tensioning pulley suspended from the bar to act upon its lower course. Thus, whenever by change or adjustment a strand which was formerly ele- 35 vated to form a side of a stall is allowed to descend so as to become part of the traveling floor, it will not be permitted to sag, and on the other hand elevation of any particular strand does not affect the tensioning 40 and level of the other strands.

At the delivery or exit end of the belt, a scraper plate 23 is secured detachably and adjustable to the under sides of arms 24 which are mounted by means of rods 25 and 45 spacers 27 in upwardly and rearwardly inclined positions in the frame of the machine and carry the pulley shaft 5 in their upper ends. This plate is slotted transversely from its upper rear edge in such manner that the 50 slots receive the under parts of the pulleys 4, while the fingers 28 extend between the pulleys to points adjacent and in rear of their axial centers. The edges of the slotted portion of the scraper plate or comb approach sufficiently close to the sides and periphery of the pulleys to clear the same effectively of coating material, which tends to accumulate thereon and which if not removed is detrimental to the product of the 55 machine. The chocolate taken off by the scraper falls or is conveyed into the tank below.

The strands 1 pass from the rear guide pulleys 4 downward behind and under the 60 scraper plate 23 to grooved roller sleeves 29,

which are supported rotatably on the spacers 27 of the lower rod 26, and thence forward to the tensioning pulleys 21. This, in conjunction with the entrances 22 or other formation of the blocks 20 facilitating removal, 70 enables any one of the separate strands composing the belt to be easily and quickly taken out and replaced without disturbing the remaining strands or other parts of the machine. 75

What I claim as new is:

1. In a confectionery-coating machine having means for supplying coating to the confections, the combination with a belt for conveying the coated confections, the said 80 belt being composed of longitudinal strands, of means for elevating certain of the strands in the upper course to form compartments or stalls for the confections to prevent lateral displacement, and means for 85 individually tensioning each of the strands in a lower course.

2. In a confectionery-coating machine having means for supplying coating to the confections, the combination with a belt for 90 conveying the coated confections, the said belt being composed of longitudinal strands, of a cross-bar between the upper and lower courses of the belt, a series of elevating pulleys relatively few in number supported by 95 said bar to engage certain of the strands in the upper course, and a numerous series of individual spring suspensions and pulleys depending from the bar to tension all the strands in the lower course. 100

3. In a confectionery-coating machine having means for supplying coating to the confections, the combination with a belt for conveying the coated confections, the said belt being composed of longitudinal strands, 105 of a cross-bar between the upper and lower courses of the belt, a carrier detachably mounted on said cross-bar and carrying a series of elevating pulleys relatively few in number supported in upward projecting relation by said bar to engage certain of the strands in the upper course, and a numerous series of individual tensioning devices supported from the bar and engaging all the strands in their lower courses. 110

4. In a confectionery-coating machine having means for supplying coating to the confections, the combination with a belt having a substantially horizontal upper course for conveying the confections, the 115 said belt being composed of longitudinal strands, of a series of individual tensioning devices co-operating with the several strands in their lower courses.

5. In a confectionery-coating machine 125 having means for supplying coating to the confections, the combination with a belt having a substantially horizontal upper course for conveying the confections, the said belt being composed of longitudinal 130

strands, of a cross-bar between the upper and lower courses of the belt, springs hung from said cross-bar, and pulleys carried by said springs and urged upward thereby to 5 tension the strands.

6. In a confectionery-coating machine having means for supplying coating to the confections, the combination with a belt having a substantially horizontal upper course 10 for conveying the confections, the said belt being composed of longitudinal strands, of a cross-bar between the upper and lower

courses of the belt, a series of spring suspensions hung from the cross-bar, and independent blocks carried by said suspensions 15 and containing pulleys urged upward thereby against the lower courses of the strands to tension the same, said blocks being provided each with an entrance permitting the introduction and removal of its strand, 20 whereby to permit any one of the tensioned strands composing the belt to be removed and replaced without disturbing the others.

PANAYIOTIS D. PANOULIAS.
